ROLLER SCREEN

Benjamin Gornetski, Laplume, Pa.

Application June 27, 1940, Serial No. 342,819

6 Claims. (Cl. 156—39)

This invention relates to an improved construction of roller screen for windows and more particularly to a roller screen construction especially adapted for use on windows provided with sliding sashes.

It is a primary aim of the invention to provide a device adapted for use on window frames of various widths and lengths in conjunction with window screens of various sizes, for mounting spring shade rollers of various lengths on which the screen is adapted to be wound.

Still another aim of the invention is to provide a window screen having means whereby the screen fabric may be wound on a roller, when not in use, and disposed within a cover to protect the screen from the elements, said cover being yieldably mounted by resilient brackets in window frame openings on the outer sides of the window sashes in a manner so that the cover and window screen may be readily lifted out of their supporting brackets from the inner side of the window when it is desired to entirely remove the screen from the window, as during the winter season.

Still another aim of the invention is to provide a novel construction of roller window screen including a cover formed of extensible, telescoping sections for receiving the window screen when in a retracted position, and guide members formed of extensible, telescoping sections having channel portions for slidably engaging the side edges of the window screen when in an extended position.

Other objects and advantages of the invention will hereinafter become more fully apparent from the following description of the drawings, which illustrate a preferred embodiment of the invention, and wherein:

Figure 1 is a front elevational view showing the invention applied to the outer side of a window frame and in an extended position.

Figure 2 is an enlarged longitudinal vertical sectional view taken substantially along the plane of the line 2—2 of Figure 1.

Figure 3 is a horizontal sectional view on an enlarged scale, taken substantially along the plane of the line 3—3 of Figure 1.

Figure 4 is an enlarged vertical sectional view taken substantially along the plane of the line 4—4 of Figure 1.

Figure 5 is a fragmentary, enlarged horizontal sectional view, taken substantially along the plane of the line 5—5 of Figure 1.

Figure 6 is a fragmentary view of a portion of the screen fabric,

Figure 7 is a vertical sectional view, partly in elevation, of one of the latch members, and

Figure 8 is a horizontal sectional view taken substantially along the plane of the line 8—8 of Figure 7.

Referring more particularly to the drawings, wherein like reference characters designate like or corresponding parts throughout the different views, 10 designates generally a conventional window frame including a sill 11 and side rails 12 in which are slidably mounted a pair of sashes 13. These elements, being of conventional construction, are shown merely to illustrate the application of the improved window screen, designated generally 14, and comprising the invention.

The window screen construction 14 includes a hollow roller 15, as best seen in Figure 5, through which extends a shaft 16 which is provided with a round end 17 and a square end 18, which ends project beyond the ends of the roller 15. A spiral spring 19 is mounted on the shaft 16 and is fixed at one of its ends by means of a fastening 20 to the shaft 16 and at its opposite end by means of a similar fastening to the roller 15 for turning the roller in one direction relatively to the shaft. An elongated strip of mesh wire fabric 21 is secured at one end to the roller 15 and is wound therearound in a direction so that when the roller 15 is actuated by the spring 19 it will wind the fabric strip 21 thereon. The strip 21 is provided with enlarged reinforced side edges 22 which are likewise flexible to be wound on the roller 15. The free end of the strip 21 is mounted in and secured to a rigid channel shaped member 23 by means of the fastenings 24.

A cover, designated generally 25, is formed of an intermediate section 26 and a pair of corresponding end sections 27 which are disposed in telescoping engagement with the ends of the intermediate section 26 to provide the extensible cover 25. The cover sections 26 and 27 are rolled lengthwise to form a restricted slot 28 in the under side of the cover 25. The intermediate section 26 has its longitudinal edges rolled outwardly to form the portions 29 in which are slidably mounted the inwardly curved longitudinal edges of the sections 27, which form the portions 30. As best seen in Figure 5, the remote ends of the sections 27 are closed by the walls 31. A roller bracket 32 is mounted in one of the sections 27 and a roller bracket 33 is mounted in the other section 27. The roller brackets 32 and 33 each include a flange 34 which extends toward and is secured to the inner side of a wall 31, as by means of soldering, as at 35. The brackets 32

and 33 each include a plate portion 36 which is spaced inwardly from the wall 31 of section 27, in which it is mounted. As best seen in Figure 4, the plates 36 are each provided with upwardly diverging slots 37 which open outwardly of the upper edge thereof and which terminates at its lower, restricted end in a restricted slot. The restricted slot of the bracket 32, designated 38, is sized to loosely engage the end 17 of the shaft 16. A restricted slot 39 of the bracket 33, as best seen in Figure 5, is substantially larger and is provided with parallel sides to snugly engage opposite sides of the squared end 18 of the shaft 16 to thereby key the shaft 16 to the cover 25 so that the roller 15, when actuated by the spring 19, will turn relatively to the shaft 16.

A pair of corresponding guide members, designated generally 40, each includes a strip 41 and a strip 42 of sheet metal. The strips 41 and 42 are bent lengthwise to form base portions 43 and the channel portions 44. The base portion 43 and channel portion 44 of each strip 42 is slidably mounted in the portions 43 and 44, respectively, of the complementary strip 41. It will thus be seen that the connected strips 41 and 42 combine to form extensible base members 45 which are adapted to be disposed in the inner faces of the side rails 12, on the outer side of the sashes 13, and to be secured to the rails 12 by means of fastenings 46 which extend through the base portions 43 and which hold the strips 41 and 42 of each of the base members 45 in adjusted positions. The two base members 45, before being secured by the fastenings 46 to the rails 12, are adjusted to the same length, and are attached so that they are disposed in opposed relationship to each other with the channel portions 44 thereof extending inwardly of the opening of the window frame 10. The upper sections 42 of each of the base members 45 are provided with outwardly extending flanges 47, as best seen in Figure 4. Referring back to Figure 3, the guides 40 also include the extensible guide members 48 formed of telescoping sections 49 and 50, each of which are formed of an elongated strip of sheet metal folded lengthwise and with each of the sections 50 mounted within the complementary sections 49. The intermediate portion of the pairs of sections 49 and 50 are compressed to form the shank portions 51 of the guide members 48, which shank portions are mounted in the channel portions 44 of the base members 45. The longitudinal edges of the pairs of strips 49 and 50 are shaped to form inwardly opening channel portions 52 to slidably receive the edges 22 of the screen 21. The channel portions 52 are provided with restricted outer ends to prevent the edges 22 from being detached therefrom except through the upper ends thereof. The channel members 48 are extended to substantially the same length as their supporting base members 45, after which they are secured in adjusted positions by means of fastenings 53, which extend through aligned drilled apertures 54 in the channel portions 41 of the shank portions 51, to secure guide members 48 to the base members 45 to thereby fixedly mount each of the guides 40 on a side rail 12. The upper sections 50 of the guide members 48, at their upper ends, extend above the channel portions 44 and are bent to form upwardly opening channel members 55 which rest on the flanges 47 and on which are adapted to be mounted the portions 29 and 30 of the ends of the cover 25 to thereby align the slot 28 with the channels 52.

As best seen in Figures 2, 7 and 8 the sill 11 is provided with one or more stationary keepers 56, each of which is provided with an upwardly offset intermediate portion 57, having an opening 58 provided with an outwardly projecting slot 59, in communication therewith. A corresponding number of latch elements 60 are mounted on the inner side of the member 23. Each of the latch elements 60 includes a support and bearing member 61 in which is journaled a stem 62 having a depending lower end provided with an outwardly projecting lug 63. A handle 64 is secured by a fastening 65 to the upper end of the stem 62 to combine with the lug 63 for retaining it in engagement with the support and bearing 61. The handle 64 is primarily adapted to be used for turning stem 62 to align the lug 63 with the slot 59 of the complementary keeper 56, so that said lug may pass through the slot 59 as the stem moves in to the opening 58 after which the handle 64 may be turned in either direction to move the lug 63 out of registry with the slot 59 and thereby latch the member 23 to the sill 11 to hold the screen 21 in an extended position, as illustrated in Figure 2.

A strand of wire 66 is associated with each of the guides 40. Each of the strands of wire 66 is provided with a looped end 67 forming an eyelet to receive a fastening 68 for securing the strand to a rail 12 on the outer side of the cover 25, and adjacent the top thereof. The strand 66 extends downwardly from the looped end 67 around the lower portion of the outer side and end of the cover 25 and through a space 69, as seen in Figure 1, behind the flange 47. The intermediate portion of the strand 66 is folded back upon itself to form a shank portion 70 which extends downwardly along the inner side of the channel portion 41 of the guide member 40, with which it is associated, and is provided at its lower end with an eyelet 71. The eyelet 71 of the shank 70 is secured by a fastening 72 to the aforementioned rail 12 and to the base portion 43, through which the fastening 72 extends. The opposite end 73 extends upwardly and terminates beneath the horizontal center of the cover 25. The end 73 resiliently engages the inner side of the cover 25 to cooperate with the opposite end of the strand 66 to form a resilient bracket 74 which resiliently retains the end of the cover 25 in engagement with the channel member 55. It will thus be seen that the pair of brackets 74, as illustrated in Figure 1, resiliently hold the cover 25 in place on the upper ends of the guides 40 and provides means whereby the cover 25 may be removed readily from the window frame 10 but only through the inner side thereof, when the sashes 13 are both lowered, so that the cover 25 cannot be removed from the outer side of the window frame to thereby prevent the cover and screen being removed by an unauthorized person.

The end of the reinforcing member 23, which is connected to the free end of the screen 21, terminates adjacent to the guides 40 to combine therewith to retain the side edges of the screen 21 in the channel portions 52. The member 23, at its lower end, is of sufficient width so that it will not pass through the passage 28 to thereby provide means to be grasped for drawing the screen 21 outwardly of the cover 25, when the screen is in a fully retracted position. The member 23 thus retains portions of the side edges of the screen 21 in engagement with the channels 52, when the screen is in a fully retracted position.

tion, and also closes the passage 28 so that the screen 21 will be protected from the elements when not in use and when disposed within the cover 25.

Assuming the screen 21 to be in a retracted position, wound on the roller 25, the reinforcing member 23 may be grasped to extend the screen and to close the space between the guides 40, cover 25 and sill 11 by pulling the screen downwardly until the member 23 is in an abutting engagement with the sill 11, after which latch members 69 are connected to the keepers 56 to thereby retain the screen in an extended position. When the screen is thus moved toward its extended position the roller 15 is turned in a counterclockwise direction, as seen in Figure 2, thereby causing the spring 19 to be tensioned so that when the latches 69 are released the spring 19 will rewind the roller 15 in a clockwise direction to move the screen fabric 21 to a fully retracted position. In this latter position, as heretofore described, the screen is protected from the elements and may be removed with the cover 25 from the brackets 74 through the inner side of the window frame 10, for storage, as for example, during the winter season when the screen is not required. The guides 40 may be left in place, or, if desired, may likewise be removed by removing the fastenings by means of which they are attached to the rails 12.

It will be obvious that rollers 15 of various lengths may be used with strips of screen fabric 21 of different widths to accommodate window frames of different widths and the cover 25 may be extended or retracted to adapt it to window frames of different widths. The device may also be mounted for screening a portion of the opening of a window frame or for screening the entire opening and the guides 40 may be extended or retracted to accommodate the device to window openings of different lengths and to provide means whereby different portions of the window opening may be screened.

Various modifications and changes are contemplated and may obviously be resorted to as only a preferred embodiment of the invention has been disclosed.

I claim as my invention:

1. In a roller type window screen, an extensible cover for a roller and a flexible mesh wire fabric screen wound thereon, said cover having a slot in its under side extending from end to end thereof through which the screen is movable, a channel shaped guide member formed of telescopic sections attached to a side rail of a window frame, said guide member having a horizontal channel portion at its upper end for receiving an end of the cover for detachably mounting the cover and for positioning the slot thereof in alignment with the channel of said guide member, whereby said screen can be moved through the slot of said cover with a longitudinal edge of the screen disposed in said channel shaped guide member and an arcuately shaped resilient bracket secured to a side rail of a window frame for releasably retaining the cover in position on said guide.

2. A mounting for a spring actuated window shade roller having a strip of flexible material se-

cured at one end thereto and wound thereon, comprising a cover, for said roller and the rolled portion of said strip, formed of telescopic sections and provided with a slot in the under side thereof extending from end to end thereof to form a passage for the strip, and arcuately shaped bracket member secured to a side rail of a window frame for releasably engaging an end of the cover for mounting the cover in the opening of the window frame.

3. A mounting for a roller type window screen, comprising a cover, for enclosing the roller and the wound portion of the screen, formed of a plurality of telescopic sections, said cover having a slot in the under side thereof for the passage of the screen therethrough, a channel shaped guide member, formed of extensible sections, secured to a side rail of a window frame, an end of said cover being supported on the upper end of said guide member and arranged thereby to position the slot of said cover in alignment with the channel portion of the guide member whereby a side edge of said screen will be positioned to slidably engage in said channel portion, and a resilient bracket secured to said side rail for frictionally engaging said end of the cover for retaining it in position on the guide member, said bracket engaging around the major portion of the outer side of the cover to combine with the window sashes, when closed, to prevent removal of the cover.

4. A support for roller type window screens comprising a bracket member formed of wire and connected to a side rail of a window frame for detachably and frictionally engaging a cover containing a roller and window screen wound thereon for mounting the parts on the outer side of the sashes of the window and in close proximity thereto, said bracket being engageable around the major portion of the outer side of the cover to cooperate with the sashes, when closed, to prevent removal of the cover from the window frame.

5. A device as in claim 4, comprising an elongated channel shaped guide member connected to said bracket and to said side rail of the window frame and arranged for slidably receiving a side edge of the window screen.

6. A supporting means for roller type window screens, comprising an elongated channel shaped guide member, mounted on a perpendicular side rail of a window frame, a cover provided with a slotted opening in the bottom thereof for containing a roller and a strip of screen fabric wound thereon, said cover being removably mounted, at one of its ends, on the upper end of said guide member, said strip of screen fabric having one end extending through the slot in said cover, and slidably engaging the channel portion of said guide member, said guide member forming means for supporting an end of the cover and screen and for holding the screen, when extended, in a poshaped resilient bracket secured to the side rail for closing the window opening, an arcuately of the window frame, for releasably engaging said end of the cover and for frictionally holding the cover in position on the upper end of the guide member.

BENJAMIN GORNETSKI.
